PROCESS FOR THE REDUCTION OF GRAIN
AND ITS SUBSEQUENT CONVERSION INTO
BREAD OR LIKE PRODUCTSchachna Maurice Salomon and Sune Busch,

In Great Britain February 11, 1935

4 Claims. (Cl. 83—42)

This invention is concerned with the reduction of whole grain or bran by a process which eliminates the usual conversion to flour and effects the bursting or breaking down of the aleurone and germ cells and their retention in the product.

In ordinary milling processes the grain is subjected to a number of breaks during which the bran or outer husk and the germ are separated out and rejected leaving only the endosperm which is converted into white flour.

In the process with which the present invention is concerned when dealing with the grain a wholemeal dough is produced containing the whole of the berry and in such a manner that both the aleurone and germ cells are broken down thereby rendering digestive what was previously non-digestive. This breaking down of the cells has heretofore been proposed to be effected by either of two methods one of which may be termed the mechanical method and the other the automatic method.

In the mechanical method the grain after being soaked or steeped in water is transferred to a pressure applying device such as an autoclave wherein the soaking is completed under pressure to produce swelling. The swelled grain or bran is then milled with the object of breaking down the cells.

In the automatic method the grain is firstly ground into meal, then soaked or steeped in water and then subjected to a continuously increasing pressure to cause penetration of the water through the walls of the cells. In this automatic method bursting is attempted by suddenly releasing the pressure such as by exposing the treated mass to a vacuum with the object of explosively opening out the cells.

In both of the above methods there is an element of uncertainty. For instance in the mechanical method reliance is placed upon treatment in an ordinary roller milling machine for bursting the swelled cells.

In the automatic method reliance must be had upon effective penetration of the walls of the cells by the liquid in which they are soaked as a result of the externally applied pressure and the use of any internal pressure thus produced to effect bursting when the external pressure is released.

In a similar process for milling bran it is introduced with water in excess into a vessel such as an autoclave wherein it is subjected to a continuously increasing pressure, up to about 50 atmospheres to produce swelling of the albumen.

After this treatment the bran is mechanically

milled in an attempt to effect bursting the cells.

From experiments carried out with the above processes we have found that bursting or breaking down of the cells takes place only to a very limited extent.

The principal object of the present invention is to provide a process for treating whole grain or bran which will be commercially practicable and which will result in the breaking down or bursting of the greater proportion of the aleurone and germ cells.

A further object of the invention is to provide a process which can be carried out as a continuous process and in which pressure applying devices such as autoclave may, if desired, be dispensed with.

Our experiments have shown us that it is unnecessary to bring the aleurone cells into a swollen condition before they can be burst or broken down. By subjecting the grain or bran to a crushing process to render the same sufficiently liquid absorbing we have found that simply soaking the same in water will soften the walls of the cells sufficiently as to render the same amenable to bursting by compression. Simple compression alone however such as by passing soaked but non-swelled material through pressure rolls does not act with the efficiency and rapidity required in a commercial process. We have found however, that if crushed and soaked material is subjected to combined compression and attrition whilst in a sufficiently attenuated condition that 90% and over of the cells will be broken down and that such process can be carried out continuously and expeditiously. To effect bursting by compression alone it is advisable firstly to swell the crushed product.

Broadly the present invention consists of a process for the reduction of whole grain or bran which comprises crushing the grain or bran to render the same sufficiently liquid absorbing, soaking the crushed product, preferably at atmospheric pressure, to soften the cells, and then breaking down the cells by subjecting the soaked product to compression, preferably combined with attrition, whilst in a sufficiently attenuated condition, preferably in the form of a thin film.

We have found that the soaking of the crushed grain or bran may be effected quite satisfactorily in an open vessel; conveniently in the pan of a conventional dough mixer, the soaking period being from two to three hours according to the nature of the grain or bran. We have also found that the combined compression and attrition may be applied to the dough in a most ex-

peditious and satisfactory manner by means of a machine comprising a plurality of metal rolls of comparatively large diameter having highly polished peripheries said rolls being rotated at 5 relatively different speeds and forcible towards each other by pressure applying means.

In use in the present process the rollers are set with their peripheries about .0020" apart to permit of the entrainment of a film of dough. 10 Pressure is then applied to the rotating rollers until the issuing dough is in the form of a very thin unbroken film. The pressure needed for this purpose is considerable and the resulting compression of the dough combined with the 15 attrition produced by the differing speeds of the rollers has been found to be sufficient effectively to break down both the aleurone and germ cells of the grain.

The resulting product in the case of whole 20 grain after being conditioned by the addition of yeast salt etcetera in a dough mixer is converted into wholemeal bread or like product by the ordinary baking processes.

Where bran alone has been treated by this 25 process the same may be converted into bread by adding to it a suitable percentage of ordinary flour the whole being then mixed together with yeast salt etcetera in a dough mixer after which it is converted into bread by the ordinary baking 30 processes.

The term soaking when employed in the general sense is intended to cover both simple soaking at atmospheric pressure or pressure soaking such as in an autoclave to effect a swelling 35 of the crushed products. Swelling will of course occur also to a limited extent by osmotic penetration by the non-pressure method it depending of course upon the period the product is allowed to soak.

40 In order that the invention may be clearly understood and carried into effect a plant for treating whole meal such as wheat and a plant for treating bran alone will now be described by aid of the diagrammatic accompanying drawings in which:—

45 Fig. 1 is a flow sheet illustrating the plant for treating the whole wheat and Fig. 2 is a flow sheet illustrating the plant for treating bran alone.

Referring to the plant illustrated in Fig. 1, the 50 wheat in the form of the whole berry after having been preliminarily cleaned by conventional methods is fed to a warehouse separator A wherein further cleaning takes place. The berries then pass in succession through a wheat 55 scourer B and wheat brush C respectively. The berries thus cleaned and retaining the husk or bran, are then passed through a three high wheat crushing mill D which reduces the whole berry to a granular form of such fineness as to render 60 the same readily liquid absorbing. The crushed product from the mill is then deposited in a soaking bowl E containing water wherein it remains as a mass for a soaking period of anything from two to three hours according to the 65 nature of the grain. After this period the cell walls have become sufficiently softened for the breaking down process to be effected. The soaked mass is then conveyed to a cell breaker 70 F wherein it is subjected to combined compression and attrition whilst in the form of a thin film.

The cell breaker in the plant illustrated is a machine which broadly comprises a plurality of 75 smooth surfaced contacting rollers which are ro-

tated at differing speeds with their peripheries in hard contact with each other. As previously explained the rollers are set with their peripheries about two thousandths of an inch apart to permit of the entrainment of a film of dough. The 5 rollers are then forced hard together whilst they are rotating with the result that the dough is subjected to very drastic compression and attrition and issues at the delivery end in the form of a very thin unbroken film from which most 10 of the water has been extruded and in which nearly all the bran and other cells as well as the germ have been broken down. This latter fact has been clearly demonstrated by microscopic examination of the resulting product. From the 15 cell breaker the reduced product consisting of the whole wheat berry including the bran is then taken to a dough mixer not shown wherein it is conditioned by the addition of yeast, salt, etcetera. It then goes through the normal baking 20 processes for conversion into whole meal broad or like product.

In the plant for treating bran alone the material after having passed through the usual 25 cleaning processes, is fed through one pair of rolls of a four roller mill G. The partially reduced product is then delivered to a sieve H which separates out the tailings which are elevated to the four roller mill G for passage between the second pair of, rolls of the same, and 30 re-entry into the sieve. From the sieve the bran passes through a single roller mill I and thence to a centrifugal dresser J. This process is repeated in a further roller mill K and centrifugal dresser L. From each dresser a return is provided for effecting a re-entry of the coarser particles to the feeds to the respective roller mills. By this means the bran particles are reduced to 35 approximately the same size.

The crushed bran is then fed into a liquid 40 mixer M, to ensure that the particles shall each take up a certain amount of water. The sodden mass is then transferred to a soaking bowl N wherein it is left for from two to three hours to soften the cells. The soaked bran is then conveyed to the cell breaker O which is the same 45 as used in the wheat plant illustrated in Fig. 1. The treatment to which the soaked bran is subjected in the cell breaker is the same as in the case of the whole wheat. The bran thus treated by this process may be converted into bread by adding to it a suitable percentage of ordinary flour, the whole being then mixed together with yeast, salt, etcetera in a dough mixer after which it passes through the ordinary baking processes. 50

Although simple soaking in an open soaking 55 bowl has been found sufficient to effect the required softening of the cells and germ, the crushed grain or bran may be caused to swell by introducing the same into an autoclave containing liquid and therein subjecting the same to the pressure required for the purpose. As however the operation of the autoclave adds somewhat to the cost of the process and as its use is unnecessary it is preferred to dispense with it. 60

Similarly whilst compression alone has been found sufficient to break down the cells its action is so uncertain and slow as compared with breaking down by subjection to combined compression and attrition that the latter method is 65 preferred. It must be understood however that the use of the autoclave and/or compression in a process according to this invention is not disclaimed but comes within the broad definition 70 of the invention set forth in the opening state- 75

ments of the specification and in some of the appended claims.

It is also to be understood that the soaking bowl used in both plants may form part of a conventional dough mixing machine in which case the separate liquid mixer M may be dispensed with, mixing and soaking being effected in a single machine.

Having now particularly described and ascertained the nature of our said invention and in what manner the same is to be performed, we declare that what we claim is:—

1. Process for the production of a cereal substance including aleurone cells which comprises the steps of firstly partially milling the cereal substance to reduce the same to a product of substantially powdered form capable of absorbing liquid upon simple soaking which contains the cells in a substantially unreduced form soaking the partially milled product for a period of time sufficient to soften and swell said cells and finally subjecting the soaked and softened product to combined compression and attrition by causing the same to pass between pairs of smooth rollers rotating at differing speeds said rollers being forced together with a pressure sufficient to squeeze and rub said product into a thin film and to break down the walls of the softened cells by the action of the pressure applied during such squeezing and rubbing.

2. Process for the production of bread from whole grain including the bran comprising the steps of firstly partially milling the whole grain berries with their bran coverings to reduce the whole to a flour form which contains the aleurone and germ cells in a substantially unreduced form, soaking the partially milled product for a period of time sufficient to soften and swell said cells, subjecting the soaked and softened product to combined compression and attrition by causing the same to pass between pairs of smooth rollers rotating at differing speeds said rollers being forced together with a pressure sufficient to squeeze and rub said product into a thin film and to break down the walls of the softened cells by the action of the pressure applied during rubbing and squeezing and finally subjecting the dough like product after being conditioned by the addition of yeast, salt, etcetera, to the ordinary bread baking processes.

50

3. Process for the production of bread from bran which comprises the steps firstly of partially milling the bran to reduce the same to a product of substantially powdered form capable of absorbing liquid upon simple soaking and which contains the cells in a substantially unreduced form, soaking the partially milled product for a period of time sufficient to soften and swell the cells, subjecting the soaked and softened product to combined compression and attrition by causing the same to pass between pairs of smooth rollers rotating at differing speeds said rollers being forced together with a pressure sufficient to squeeze said product into a thin film and to break down the walls of the softened cells by the direct action of the rubbing and squeezing to which they are thereby subjected, adding to the dough-like product a suitable percentage of flour obtained from the berry of the grain, simultaneously mixing and conditioning the same and finally subjecting the mixed and conditioned product to the ordinary bread baking processes.

4. Process for the production of bread from bran which comprises the steps of firstly partially milling the bran to reduce the same to a product of substantially powdered form capable of absorbing liquid upon simple soaking and which contains the cells in a substantially unreduced form, soaking the partially milled product for a period of time sufficient to soften and swell the contained cells, subjecting the soaked and softened product to combined compression and attrition by causing the same to pass between pairs of smooth rollers rotating at different speeds said rollers being forced together with a pressure sufficient to squeeze and rub said product into a thin film and to break down the walls of the softened cells by the direct action of the rubbing and squeezing to which they are thereby subjected, adding to the dough-like product a suitable percentage of flour which contains cells in a broken down condition and which is obtained by similarly treating the berry of the grain, simultaneously mixing and conditioning the dough-like product and the added flour and finally subjecting the mixed and conditioned product to the ordinary bread baking processes.
